Patented Mar. 13, 1900.

E. C. HISCOCK.

SELF PLAYING INSTRUMENT.

(Application filed June 19, 1899.)

(No Model.)

UNITED STATES PATENT OFFICE.

EMORY C. HISCOCK, OF CHICAGO, ILLINOIS, ASSIGNOR TO THE
W. W. KIMBALL COMPANY, OF SAME PLACE.

SELF-PLAYING INSTRUMENT.

SPECIFICATION forming part of Letters Patent No. 645,172, dated March 13, 1900.

Application filed June 19, 1899. Serial No. 721,073. (No model.)

To all whom it may concern:

Be it known that I, EMORY C. HISCOCK, a citizen of the United States, residing in Chicago, in the county of Cook and State of Illinois, have invented a new and useful Improvement 5 in Self-Playing Instruments, of which the following is a specification.

This invention relates to self-playing organs; and it consists in the novel construction of parts and devices, substantially as hereinafter set forth, whereby all or any number of a series of stops can be put into or out of service, as determined by the music-sheet.

The invention also relates to the construction 15 of the means whereby the music-sheet controls said device.

The nature of the invention will be fully disclosed from the description given below when considered with reference to the accompanying drawings, in which—

Figure 1 is an elevation, partly in section, of those parts of a self-playing organ to which the invention relates; and Fig. 2 is a partial plan of the music-sheet.

In said drawings, A represents a cylinder 25 supplied at one end with compressed air by the pipe A' and open to the atmosphere at the other end, as seen at A². A piston A³ is movable longitudinally through this cylinder 30 by means presently to be described, the normal position of the piston being that illustrated. At intervals throughout the length of the cylinder are pipes A⁴, connecting it with different stops or groups of stops of the organ

35 and each acting to put the stop or stops with which it connects into service when the pressure from the pipe A' is cut off from it by the backward movement of the piston A³ away from the opening A². By moving the piston 40 in the direction stated a crescendo effect will obviously be produced, as such movement will bring the stops into service successively as their pipes A⁴ are uncovered by the piston and allowed to exhaust, a full stroke of the 45 piston uncovering all said pipes and bringing all the stops into action, and thus producing a maximum of sound, and partial strokes producing less marked effects, according to the number of said pipes uncovered. Diminuendo 50 endos are produced by the movements of the

piston A³ in the other direction, in which the high air-pressure is again admitted to said pipes A⁴ in succession, as will be understood, and of course the extent to which the sound is lessened depends upon the extent of such 55 movement by the piston.

To operate the piston A³, I provide the following mechanism: Attached to the stem A⁵ of the piston is a rack-bar B, having racks upon its opposite sides, each consisting of 60 teeth corresponding to the number of pipes A⁴, and opposite said racks are spring-pressed pawls B' B², each adapted to engage the face of the rack nearest it. Said pawls are normally held out of engagement with the rack 65 by stationary pins or guides B³; but they are released from these guides by the longitudinal movement of the pawls received from their operating-pneumatics B⁴ B⁵ as soon as they have moved far enough to carry the offsets B⁶ beyond the guides. Each pawl is provided with its own pneumatic. The springs which throw the pawls into engagement with the racks when they have moved far enough 70 to free them from the guides are shown at B⁷. 75 The longitudinal movements of the pawls are due to the inflating and deflating of the pneumatics, the deflating being aided in the usual manner by a spring, (not shown,) and for this purpose they are preferably attached directly 80 to the moving sides of the pneumatics, as thereby the latter exert a direct push and pull upon them; but they may be otherwise connected together, if desired.

The inflating and deflating of the pawl-operating pneumatics is controlled by the main music-sheet of the instrument, so that the operating of the crescendo and diminuendo device is rendered as truly automatic as the operating of the valves which cause the speaking 85 of the pipes or reeds. I accomplish this as follows: The music-sheet shown at C is provided, preferably upon opposite sides, with perforations C' and C², one set of perforations causing the crescendo effect and the other the diminuendo. The tracker-range D is of course provided with special air-ducts D', each registering with one set of said perforations in the music-sheet. When one of said perforations moves over its corresponding tracker-duct, 90 95 100

the air thereby admitted to the duct is conducted by the pipe D³, connecting the duct, to the under side of a membrane E, located in what may be termed the "coupler-casing" M, and 5 destroys the exhaust normally existing there and causes the lifting by the membrane of the stem E', upon which valves E² and E³ are mounted. The chamber E⁴ above the membrane is constantly exhausted and communicates with the inner side of the membrane by a minute or bleeding passage E⁵ E⁶, the right-angled part E⁵ of which regulates the capacity of the passage and is formed in a screw E⁷, inserted through the side of the casing, so as to be easily removable, and one limb of said right-angled portion leading from the chamber under the membrane and the other limb thereof registering with the part E⁶, which connects with chamber E⁴. The 15 valves E² and E³ control the air under pressure received from the pipe E⁸ and either admit such air to or cut it off from pipe E⁹. When the supply is cut off from pipe E⁹, said pipe exhausts into the open air through the 20 open chamber E¹⁰. The normal position of the valves is that shown, with the high pressure present in pipe E⁹. Said pipe E⁹ leads to a chamber above another membrane F, located in what I call the "intermediate" casing N, the space F' under the membrane being always open to the atmosphere. This 25 membrane is joined to the stem of valves F² and F³, controlling the admission of high-pressure air from chamber F⁴, which is constantly charged therewith, to the pipe G, leading 30 to the pneumatic of one of the rack-operating pawls. In the case illustrated the pipe G is shown as connecting with the pneumatic B⁴, operating the crescendo-pawl B', and in 35 the position shown, which is the normal one, the pneumatic is deflated, as pipe G has been allowed to discharge its compressed air through space F'.

It will be understood that the pneumatic 40 devices above described, serving to inflate and deflate pneumatic B⁴, and thereby to actuate pawl B' and move the piston A³ in one direction, are substantially duplicated in the case of pneumatic B⁵, so that pawl B² will actuate 45 the piston in a similar manner, but in the opposite direction. The pipe G' serves to connect pneumatic B⁵ with such duplicate action.

The operation of the apparatus is as follows: 50 In the position shown in the main figure the parts are at rest, with the tracker-ducks, the pipes G and G', and the pawl-pneumatics all exhausted and with the pipe connecting the coupler with the intermediate charged with 55 air under pressure. If the music-sheet is now set in motion and one of the perforations C' or C² therein passes over its corresponding tracker-duct, air will be admitted to the latter, which will destroy the exhaust under the 60 coupler-membrane. This causes the shifting of the coupler-valves E² and E³, the exhaust-

tion of pipe E⁹, the shifting of the intermediate valves F² and F³, the charging of the pipe leading to the pawl-pneumatic, and the inflating of the latter, so that an impulse is 65 given to the pawl actuated by the pneumatic which will cause it to carry the piston A³ a distance sufficient to uncover or cover one of the stop connections A⁴, the direction of the movement thus given the piston being determined by the perforations C' or C². Of course 70 the pawl B² cannot operate the piston until after the latter has been moved from its normal position by pawl B'. If the piston is to be moved more than one step or rack-space— 75 as, for instance, when more of a crescendo is desired than would follow the putting of a single stop in action—the perforations in the music-sheet are repeated in close order, as 80 illustrated at C³. The pipes A⁴ are enabled 85 to control the motor-channels of the several stops in any suitable way, and I have illustrated a suitable construction as applying to one of the stops in the main figure. In this construction each of said pipes leads to the 90 chamber of a separate membrane-motor J' in a casing J, and as the pipes A⁴ are normally charged with compressed air said membrane will be normally distended. Each membrane is attached to the stem J² of the valves J³ and 95 J⁴, controlling the motor-passage, by means of which the stop is thrown into action, and which passage in the case illustrated consists of the pipes J⁵ and J⁶, one leading to the stop-action and the other communicating with a 100 compressed-air supply. In the position of the valves shown the pipes J⁵ and J⁶ are in communication, so that the stop is not speaking; but if the piston A³ be moved far enough to uncover the corresponding pipe A⁴ the latter 105 will be at once relieved of the air-pressure, and the membrane J' will then collapse and allow the valves J³ and J⁴ to shift and close the communication between said motor-passage pipes and allow the pipe J⁶ to exhaust, 110 so that the stop will be thrown into action.

As many users of these instruments prefer to control the crescendos and diminuendos by the hand in the ordinary way instead of relying upon the music-sheet or other automatic means for the performance of that function, I provide means whereby the mechanism I have described may be rendered inoperative at will. These means consist of another membrane K, placed under the stem J² of the motor-channel valves and connecting the chamber of such membrane or a chamber common to all of the series of membranes K to a source of compressed-air supply by the pipe K'. By admitting the air-pressure under this membrane K the valves J³ and J⁴ will be held up in the position illustrated, so that the motor-channel cannot operate the stop, and consequently any movements of the piston A³ taking place while said valves are thus held will 120 be inoperative. At the same time the stops are free to be manipulated by hand. The 125

pipe K' is of course controlled by a suitable valve and may be charged or exhausted at will.

To prevent any overthrow by the piston A³ and to hold the piston firmly in any position to which it may be moved by the pawls and also to overcome any displacing tendency exerted upon it by the air-pressure from pipe A', I extend the rack, as shown at H, and corrugate one of the surfaces of such extension and combine with it a spring-pressed roller H'. The operation of this device will be clearly understood from Fig. 1.

I claim—

1. The combination in a self-playing instrument with a series of stop-actions, of a device for successively putting all or any number of said actions into or out of service, means for giving said device a step-by-step movement, and means whereby the music-sheet controls said actuating means, substantially as specified.

2. The combination in a self-playing instrument, of a device for causing crescendo and diminuendo effects, a double rack-bar for actuating said device, spring-pawls moving said rack in opposite directions, and pneumatics for actuating said pawls, substantially as specified.

3. The combination in a self-playing instrument, of a device for causing crescendo and diminuendo effects, a double rack-bar for actuating said device, spring-pawls moving said rack in opposite directions, pneumatics for actuating said pawls, and a music-sheet controlling said pneumatics, substantially as specified.

4. The combination in a self-playing instrument, of a device for causing crescendo and diminuendo effects, a double rack-bar for actuating said device, spring-pawls moving said rack in opposite directions, pneumatics for actuating said pawls, a music-sheet, and means whereby said sheet controls said pneumatics, substantially as specified.

5. The combination with a crescendo and diminuendo device consisting of the cylinder A and piston A³, of the rack-bar attached to the piston, the pawls engaging the bar and moving the piston in opposite directions, pneumatics actuating said pawls, and means for inflating said pneumatics, substantially as specified.

6. The combination with means for producing crescendo and diminuendo effects having an operating device such as the piston A³, of racks and pawls for actuating said device,

pneumatics moving the pawls, and a music-sheet and pneumatic-actions for controlling said pneumatics, substantially as specified. 60

7. The combination with the piston and its actuating devices, of a friction device for preventing overstrokes by the piston, &c., substantially as specified.

8. The combination with the piston and its actuating devices, of the extension H having a corrugated surface, and a spring-pressed roller riding on such surface, substantially as specified. 65

9. In a pneumatic-action, a screw E⁷ having a bleeding-passage formed in it, substantially as specified. 70

10. In a pneumatic-action, a screw E⁷ having a right-angled portion E⁵ of a bleeding-passage formed in it, substantially as specified. 75

11. The combination in a self-playing instrument, of a crescendo and diminuendo producing device controlled by the music-sheet, and means operable at will for preventing the operation of such device, substantially as described. 80

12. The combination in a self-playing instrument, of a crescendo and diminuendo producing device controlled by the music-sheet, and means for rendering the stops independent of such device, substantially as specified. 85

13. The combination in a self-playing organ, of a crescendo and diminuendo device 90 or stop, a music-sheet controlling said device and provided with a row of perforations for putting said device into action and another row of perforations for putting said device out of action, tracker-ducts corresponding to 95 said perforations, and pneumatic means for operating said device, substantially as specified.

14. The combination in a self-playing organ, of a series of stop-actions, a device for throwing all or a portion only of said actions into and out of service, and pneumatic means for operating said device, said means embracing the music-sheet and tracker-range, of which the former is provided with two rows 105 of perforations and the latter with two ducts adapted to cause the operation of said device and to regulate the extent of its operation, substantially as specified.
